UNITED STATES PATENT OFFICE.

HENRY C. FRESHOUR, OF BRIDGEPORT, CONNECTICUT.

RUBBER PUMP-BUCKET.

SPECIFICATION forming part of Letters Patent No. 605,707, dated June 14, 1898.

Application filed November 11, 1897. Serial No. 658,149. (No model.)

To all whom it may concern:

Be it known that I, HENRY C. FRESHOUR, a citizen of the United States, residing at Bridgeport, in the county of Fairfield and State of Connecticut, have invented certain new and useful Improvements in Rubber Pump-Buckets; and I do hereby declare the following to be a full, clear, and exact description of the invention, such as will enable others skilled in the art to which it appertains to make and use the same.

My invention has for its object to produce a bucket for chain-pumps which shall be reversible, so as to lift water with either side, which, while sufficiently flexible at the edge to cause it to fit the bore of a pump-stock closely, shall be stiff at the hub, where rigidity is required, and which shall be so constructed as to produce a maximum of rigidity with a minimum amount of stock, my novel bucket being both light and stiff and, owing to the fact that there is no surplus stock, less expensive to produce than any practical chain-pump bucket now upon the market.

With these ends in view I have devised the novel pump-bucket which I will now describe, referring by number to the accompanying drawings, forming part of this specification, in which—

Figure 1 is a plan view of my novel pump-bucket, the side in view being the side which I ordinarily make the under side, although that is not a matter of importance; Fig. 2, an edge view, the flat side of the bucket being uppermost; and Fig. 3 is a section on the line xx in Fig. 1.

1 denotes the table of my novel bucket, the flat side of which is ordinarily placed uppermost, as shown in Fig. 2.

2 denotes the hub, which is provided with a central opening 3 to receive the shank of a chain-link, and 4 denotes brackets or supporting-ribs extending from the hub nearly to the edge of the table and serving as supports therefor, the brackets in connection with the hub being stiff enough to hold the table absolutely rigid under ordinary circumstances, but being sufficiently flexible to permit the table to yield slightly at the edges should it

be necessary in use. The number of brackets or supporting-ribs is not of the essence of my invention. In the present instance I have shown six brackets or supporting-ribs, which number I have found quite sufficient in practice.

In practice the hub, table, and brackets or supporting-ribs are molded in a single piece. It will be seen that all surplus stock is dispensed with, thus making the number of my novel buckets run higher to the pound. I have found in practice that they are sufficiently flexible at the edges to cause them to fit a pump-stock closely.

It will be observed that the radial ribs or brackets 4 are arranged edgewise vertically or at right angles to the table 1 and that they are highest or deepest at their inner ends and slope thence downward outwardly toward their outer ends, which terminate at or near the periphery of the said table. From this edgewise arrangement of the said ribs or brackets relative to said table it will be obvious that they afford a maximum amount of rigidity to support or strengthen said table with a minimum amount of stock required in their formation or construction, and they thus render the table sufficiently rigid, so that the bucket may be used either side up in lifting water; also, when thus constructed and arranged they are adapted to serve as guards to protect the edges of the bucket-table from abrasion in entering the penstock or pipe.

Having thus described my invention, I claim—

A chain-pump bucket comprising a table, a hub, and a series of radial ribs or brackets integral with the said hub and table, said ribs or brackets being disposed edgewise vertically or at right angles to said table, and being highest or deepest at their inner ends and sloping thence outwardly.

In testimony whereof I affix my signature in presence of two witnesses.

HENRY C. FRESHOUR.
